DESCRIPTION

FIG. 1 is a front, top perspective view of an otoscope, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded view of the otoscope.

The broken lines in the figures illustrate portions of the otoscope that form no part of the claimed design. The otoscope is shown with a symbolic break. The appearance of any portion of the otoscope between the break lines forms no part of the claimed design.
